UNITED STATES PATENT OFFICE.

MICHAEL F. BROGAN, OF LAWRENCE, MASSACHUSETTS, ASSIGNOR TO UNITED SHOE MACHINERY CORPORATION, OF PATERSON, NEW JERSEY, A CORPORATION OF NEW JERSEY.

MACHINE FOR SEPARATING LASTS AND SHOES.

Application filed May 12, 1921. Serial No. 489,006.

This invention relates to shoe machines, and is illustrated as embodied in a machine for separating lasts and shoes.

In separating high shoes from their lasts, it is desirable to diminish the strain on the shoes by turning back the tops of the shoe uppers to permit longitudinal withdrawal of the lasts as soon as the last heels clear the counters of the shoes. A last-pulling machine embodying means for performing this operation was first disclosed in Letters Patent of the United States No. 1,361,822, granted to me on an application filed May 19, 1915. In this machine two gripping jaws or pincers are provided, which grasp the shoe upper, one on each side, pulling it outwardly and turning it back about the shoe counter.

It is an object of this invention to improve the operation of machines of this type, as will hereinafter be fully explained. In its broader aspects, however, the invention is not limited to the particular form of last and shoe separating mechanism disclosed in the above-identified patent.

A feature of my invention is to be found in the provision of mechanism for operating the upper-turning means at the very beginning of the relative separating movement of the last and shoe, so that the upper may be turned back down to the counter stiffener at the beginning of said relative separating movement, and for thereafter holding the upper turned back until the completion of said separating movement. As illustrated, this mechanism is actuated by the beginning of the separating stroke, while all lost motion is being taken up in the separating mechanism, and its cycle is completed to turn back the upper before the actual relative movement of the last and shoe heightwise of the shoe has much more than begun. In this way the shoe upper is safely distended so as to relieve the shoe from strain such as it would otherwise be subjected to throughout the movement of the last heightwise of the shoe. This positively insures against undue stretching of the counter portion of the shoe upper by the withdrawal therefrom of the bulging rear portion of the last and thus possible injury to the back seam is avoided and the separation

of the last from the rear of the shoe is greatly facilitated.

As this turning back of the upper is completed while the last heel is still strained against the counter to provide the greatest possible clearance between last and shoe at the instep, the pincer is arranged to engage the shoe at the back-seam, and to fulcrum against the middle part of the counter while pulling the top of the counter backward. According to this novel arrangement, the length of the shoe upper is increased just at the time of maximum longitudinal strain on the shoe, and this results in a marked decrease in the longitudinal strain necessary to obviate the possibility of the last breaking the shoe out across the instep. The pincer is supported during this operation by cams which rest on cam plates carried by the usual shoe-gripping devices.

In order to facilitate the use of a single pincer engaging the shoe-upper at the back seam, my invention contemplates the use of an upper-spreading device, illustrated as a plate carried by the last support, to cam apart the sides of the shoe upper when the lasted shoe is positioned on the support.

Further features of my invention are to be found in various combinations and specific constructions which will be obvious from the following description of the embodiment of my invention shown by way of illustration in the accompanying drawings, in which.

Fig. 1 is a side elevation of the machine with the casing broken away;

Fig. 2 is a perspective view of the last support and the upper-turning means;

Fig. 3 is a perspective view of one of the shoe-gripping devices carrying a cam plate; and

Figs. 4 to 7 inclusive are diagrammatic views showing the operation of the machine.

The machine is carried by a suitable casing 10, and is actuated through a definite cycle by cams on a main shaft 12, controlled by stopping and starting mechanism 14 operated either by depression of a treadle 16 or by an upward pull on a chain 18 secured to a last support 20. The last support carries a last pin 22, on which a lasted shoe is placed, and is secured to one end of a bell

crank lever 24 arranged to be pulled downwardly to withdraw a last from a shoe by a link 26 and a lever 28 operated by a thrust-rod 30 actuated by a suitable cam on the 5 shaft 12. The outer end of the bell crank 24 is supported by a two-part spring 32, secured to the link 26 at 34. The lever 28 is yieldingly pulled upward as far as permitted by the thrust-rod 30, by means of an adjustable spring 36.

When a lasted shoe has been placed on the last pin 22, and the last support 20 is raised to position the shoe and to trip the starting mechanism 14, the first portion of 15 the rotation of the shaft 12 operates, through a suitable cam, a bell crank lever 38 which advances a push-rod 40 against the resistance of springs 42, to actuate co-operating devices 44 to grip the shoe, whereupon the link 26 is moved downwardly to pull the last out of the shoe.

The above-described parts and their method of operation may be, and are illustrated as, identical with the disclosure in my 25 co-pending application No. 192,954, filed Sept. 24, 1917, (United States Letters Patent No. 1,383,284, granted July 5, 1921) and no detailed description is therefore deemed necessary.

30 To facilitate the turning of the upper, a plate 50 is secured to the last support 20 by a screw-and-slot connection 52, in position to spread apart the sides of the upper of a lasted high shoe when it is placed on the 35 last pin 22.

The upper-gripping pincer rests in idle position on an adjustable stop 62 carried by the last support 20, and comprises co-operating jaw members 60 and 64 carried by 40 spindles 70 supported by arms 72 and 74 secured to a U-shaped member 76, and counterbalanced thereon by torsion springs 80, which support most of the weight of the upper turning device, in such a manner that 45 rearward yielding of the arms 72 and 74 will rock the member 76 about its pivotal mounting 78 and distort the torsion springs 80. The extent to which member 76 may rock is determined by an adjustable stop 82. 50 The cams 84 and 86 are mounted on the ends of the spindles 70, and are arranged to be supported by cam plates 88 and 90 carried by the shoe-gripping devices 44 and moved thereby beneath the cams 84 and 86 at the 55 beginning of the rotation of the shaft 12.

As shown in Figs. 2 and 6, the jaw 60 is pivoted to the jaw 64 at 92, and is secured to actuating arms 96 arranged to be pulled by chains 98 to close it against the jaw 64 on 60 the upper of a shoe against the resistance of a pincer-opening spring 73, and to rock the entire pincer about the spindles 70, turning back the upper, as shown in Figs. 4 to 7. The jaw 64 is carried by side arms 65 94 secured to the spindles 70. During the

rocking, the spindles 70 are supported by the cams 84 and 86 bearing on the cam plates 88 and 90, and are turned against the resistance of torsion springs 71. At the end of this turning movement, as shown in Fig. 7, 70 the jaw 60 fulcrums against the shoe at 100, the spindles 70 yielding rearwardly against the resistance of the springs 80 as far as permitted by the stop 82, thereby twisting the top of the counter at 102 rearwardly of the 75 shoe. This results in a lengthening of the shoe and a considerable relief in the strain on the shoe as the last heel is moving past the upper part of the shoe counter.

The chains 98 are pulled over pulleys 104 by links 106 secured to a lever 108 which is operated by cam rolls 110 bearing thereagainst and carried by the connection 34. Thus the first downward movement of the link 26 and the connection 34 in the pulling 80 of the last acts through a very short lever arm rapidly to operate the lever 108. As the lever arm pulling on the links 106 is relatively long, the actuation of the upper turning device is completed before the separation of the last and shoe has fairly begun (see Fig. 7). Thereafter the rolls 110 ride idly down the lever 108, holding the upper-turning pincer 60, 64 in the position shown in Fig. 7.

In operation, a last L carrying a shoe S is placed on the last pin 22, with the top of the upper between the jaws 60 and 64. The last support 20 is then lifted, pulling the chain 18 and starting the rotation of shaft 100 12. The grippers 44 move inwardly to seize the shoe, positioning the cam plates 88 and 90 below the cams 84 and 86. The link 26 begins to descend, and at the very beginning of its stroke it operates the lever 108 to close 105 jaw 60—64 and turn it about the spindles 70, supported by the cam plates 88—90, to turn back the upper and twist the counter rearwardly as shown in Fig. 7. The link 26 continues to descend, pulling the bell crank 110 24 downwardly to extract the last from the shoe as in my above-identified patents. At the conclusion of the cycle, the springs 36, 42 and 80 restore the various parts of the mechanism to their original positions.

While I have described in detail one embodiment of my invention, it is not my intention to limit its scope thereby, or otherwise than by the terms of the appended claims. The term "shoe", as used throughout the specification and claims, refers to a finished or partly-finished shoe, as the case may be.

Having described my invention, what I claim as new and desire to secure by Letters Patent of the United States is:

1. In a machine for separating lasts and shoes, in combination, a support for a last, a support for a shoe on the last, means relatively to move said supports to separate the 130

shoe and the last, and turning means to engage the shoe upper at the back-seam and double it back on itself.

2. In a machine for separating lasts and 5 shoes, in combination, a support for a last, a support for a shoe on the last, means relatively to move said supports to separate the shoe and the last, and a pincer to engage the shoe upper at the back-seam and double it 10 back on itself.

3. In a machine for separating lasts and 15 shoes, in combination, a support for a last, a support for a shoe on the last, means relatively to move said supports to separate the shoe and the last, means to spread the shoe upper, and means to turn it back out of the way of the last.

4. In a machine for separating lasts and 20 shoes, in combination, a support for a last, a support for a shoe on the last, means relatively to move said supports to separate the shoe and the last, a member on the last support to spread the shoe upper, and a pincer movable to turn it back.

25 5. In a machine for separating lasts and shoes, in combination, a last support, and a member carried by said support to engage and cam apart the sides of the upper of a shoe on the last.

30 6. In a machine for separating lasts and shoes, in combination, a last support, a member clamped to said support for spreading the upper of a shoe on the last, and means to adjust said member relatively to the support.

35 7. In a machine for separating lasts and shoes, in combination, a last-pin, a bellcrank lever to move the last pin in separating a last thereon from a shoe, and an upper-spreading plate mounted on said lever.

40 8. In a machine for separating lasts and shoes, in combination, a last-pin, a bellcrank lever to move the last pin in separating a last thereon from a shoe, and an upper-spreading plate mounted on said lever and adjustable relatively to the last-pin.

45 9. In a machine for separating lasts and shoes, in combination, a support for a last, a support for a shoe on the last, means relatively to move said supports to separate the shoe and the last, and means bodily movable to pull the shoe upper rearward relatively to the shoe bottom during the separation of the last and shoe and to double the upper 55 back on itself.

50 10. In a machine for separating lasts and shoes, in combination, a support for a last, a support for a shoe on the last, means relatively to move said supports to separate the shoe and the last, means co-operating therewith to pull rearwardly on the shoe to relieve strain on the shoe and effective in a maximum degree during the early portion of the separating movement, and a connection 60 through which the separating means actuates

the strain-relieving means to double the upper back on itself.

11. In a machine for separating lasts and 70 shoes, in combination, a support for a last, a support for a shoe on the last, means relatively to move said supports to separate the shoe and the last, and means to double back the top of the shoe upper out of the way of the last and to stretch the entire upper lengthwise to relieve the strain on the shoe 75 counter by the last heel during the separating movement.

12. In a machine for separating lasts and 80 shoes, in combination, a support for a last, a support for a shoe on the last, means relatively to move said supports to separate the shoe and the last, a pincer to grasp the shoe upper at the back seam, and mechanism to move the pincer to stretch the shoe upper 85 lengthwise to relieve the strain on the shoe counter by the last heel during the separating movement.

13. In a machine for separating lasts and 90 shoes, in combination, a support for a last, a support for a shoe on the last, means relatively to move said supports to separate the shoe and the last, and means to double the shoe upper back out of the way of the last rapidly during the first part of the separation of the last and shoe, and thereafter to hold it back until the separation is completed.

14. In a machine for separating lasts and 95 shoes, in combination, a support for a last, a support for a shoe on the last, means relatively to move said supports to separate the shoe and the last, a pincer to grasp the shoe upper, and a member movable to move the pincer to turn back the shoe upper rapidly 100 during the first part of the separating movement and to remain stationary to hold the shoe upper turned back during the remainder of the separating movement.

15. In a machine for separating lasts and 110 shoes, in combination, a support for a last, a support for a shoe on the last, means relatively to move said supports to separate the shoe and the last by movements first heightwise and later lengthwise of the shoe, a member to engage the shoe upper, and mechanism to move said member to turn the shoe upper outwardly and backwardly toward the last bottom, said mechanism being constructed and arranged to complete said upper turning movement substantially at the beginning 115 of said relative separating movement heightwise of the shoe.

16. In a machine for separating lasts and 120 shoes, in combination, a support for a last, a support for a shoe on the last, means relatively to move said supports to separate the shoe and the last by movements first heightwise and later lengthwise of the shoe, and means to double the shoe upper back on itself and to stretch it lengthwise of the 125 130

shoe, said means being constructed and arranged to complete said doubling and stretching movements before any substantial amount of relative separating movement of the last and the shoe heightwise of the shoe has occurred.

17. In a machine for separating lasts and shoes, in combination, a support for a last, a support for a shoe on the last, means relatively to move said supports to separate the shoe and the last by movements first heightwise and later lengthwise of the shoe, a pincer to engage the shoe upper at the back seam to turn the shoe upper back on itself, and means for operating said pincer to complete said turning back of the upper substantially at the beginning of the relative separating movement of the shoe and the last heightwise of the shoe to facilitate said relative heightwise movement.

18. In a machine for separating lasts and shoes, in combination, a support for a last, a support for a shoe on the last, means relatively to move said supports to separate the shoe and the last, a member to engage the shoe upper, and means to move said member bodily toward the shoe bottom and to twist it to double the upper back on itself.

19. In a machine for separating lasts and shoes, in combination, a support for a last, a support for a shoe on the last, means relatively to move said supports to separate the shoe and the last, a member to turn back the shoe upper, and a cam bodily to move said member.

20. In a machine for separating lasts and shoes, in combination, a support for a last, a support for a shoe on the last, means relatively to move said supports to separate the shoe and the last, means to grasp the shoe upper, and means carried by the shoe support to co-operate with the shoe upper grasping means in turning the shoe upper backwardly about the counter.

21. In a machine for separating lasts and shoes, in combination, a support for a last, a support for a shoe on the last, means relatively to move said supports to separate the shoe and the last, a pincer to grasp the shoe upper, means to turn the pincer including a cam, and a cam plate to co-operate therewith to move the pincer toward the bottom of the shoe.

22. In a machine for separating lasts and shoes, in combination, a support for a last, a support for a shoe on the last, means relatively to move said supports to separate the shoe and the last, a pincer to grasp the shoe upper, a cam to move the pincer toward the bottom of the shoe, and a cam plate carried by the shoe support to cooperate therewith.

23. In a machine for separating lasts and shoes, in combination, a support for a last, a support for a shoe on the last, means relatively to move said supports to separate the

shoe and the last, means including a cam to co-operate therewith in separating the shoe and the last, and a cam plate carried by the shoe support to provide a bearing for the cam.

24. In a machine for separating lasts and shoes, in combination, a support for a last and shoe arranged to be lifted manually to position the shoe in the machine, shoe-engaging members removable to grip the shoe, a spindle moved into position by the last support, a jaw eccentrically mounted on the spindle to turn back the shoe upper, cams on the spindle to lift the jaw, and cam plates carried by the shoe-engaging members and moved thereby to furnish bearing surfaces for said cams.

25. Pincer mechanism comprising a spindle, a pincer jaw carried thereby and terminating approximately in the line of the axis of the spindle, a co-operating pincer jaw in the form of a bell crank lever pivoted thereto at a point eccentric to the line of said axis, and a member to pull on said bell crank lever, to close the pincer jaws and turn them about the axis, the bell-crank lever having an arm connected to the pulling member which is curved about said axis to give an effective lever arm of substantially constant length.

26. Pincer mechanism comprising a spindle, a pincer jaw carried thereby and having its gripping portion approximately in line with the axis of the spindle, means to turn the jaw about the axis of the spindle, a cam plate, and a cam on the spindle to engage the cam plate to lift the spindle.

27. In a machine for separating lasts and shoes, in combination, a support for a last, a support for a shoe on the last, means relatively to move said supports to separate the shoe and the last, an upper turning member arranged to engage the rear extremity of the shoe, and means for actuating said member to force the top of the shoe counter backward to facilitate clearance of the last heel.

28. In a machine for separating lasts and shoes, in combination, a support for a last, a support for a shoe on the last, means relatively to move said supports to separate the shoe and the last, and a pincer to bear against a central portion of the shoe counter and twist the upper portion of the counter backward to facilitate withdrawal of the last heel.

29. In a machine for separating lasts and shoes, in combination, a support for a last, a support for a shoe on the last, means relatively to move said supports to separate the shoe and the last, oscillating arms, a pincer jaw to turn back the shoe upper, a spring connection between said jaw and said arms, and a stop to limit the oscillation of the arms.

30. For use in a machine for separating lasts and shoes which has a movable shoe gripping member, means to extract a last from a shoe gripped thereby, and a cooperating strain-relieving device comprising a cam, a cam-plate to be carried by the shoe-gripping member and moved thereby into position to be engaged by said cam.

31. Operating mechanism for a turning device comprising, in combination, a vertically movable plunger, roller means carried thereby, and a pivoted lever arranged to be connected to said device at its outer end and to be engaged by said roller means adjacent its pivoted end in such a manner that the lever is turned rapidly during the first part of the motion of the plunger and is held during the rest of said motion by

said means rolling on the surface of the lever as described.

32. In a machine for separating lasts and shoes, in combination, a support for a last, a support for a shoe on the last, means relatively to move said supports to separate the shoe and the last, a pincer to engage the shoe upper at the back seam, and means for operating the pincer to turn back the shoe upper and to twist the top of the counter backwardly away from the last, said pincer being arranged to fulcrum against the middle part of the counter while pulling the top of the counter backwardly.

In testimony whereof I have signed my name to this specification.

MICHAEL F. BROGAN.

CERTIFICATE OF CORRECTION.

Patent No. 1,634,487.

Granted July 5, 1927, to

MICHAEL F. BROGAN.

It is hereby certified that error appears in the printed specification of the above numbered patent requiring correction as follows: Page 4, line 75, claim 24, for the word "removable" read "movable"; and that the said Letters Patent should be read with this correction therein that the same may conform to the record of the case in the Patent Office.

Signed and sealed this 8th day of November, A. D. 1927.

Seal.

M. J. Moore,
Acting Commissioner of Patents.
